Tianhua Gu(57) **CLAIM**

The ornamental design for a generator motor air filter, as shown and described.

DESCRIPTION

FIG. 1 is a front elevational view of the generator motor air filter, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in the figures represent the boundary between claimed and unclaimed areas. The white areas inside the broken lines form no part of the claimed design. The portions of the article shown in broken lines form no part of the claimed design.
